ELECTRIC SWITCH

Filed May 13, 1925

UNITED STATES PATENT OFFICE.

BEN E. SPERO AND LEON SPERO, OF CLEVELAND, OHIO.

ELECTRIC SWITCH.

Application filed May 13, 1925. Serial No. 29,925.

This invention relates to electric switches and is directed more particularly to an electric switch which is enclosed in a metallic housing and commonly referred to as a 5 safety switch.

The primary object of the present invention is to provide an electric switch which shall be enclosed within a housing having a hinged cover, and the operating handle of 10 such switch projecting through the cover in such manner that opening of the cover will automatically open the switch and the electric circuit.

Another object is to provide an electric 15 switch which shall include means for permitting a plurality of the switches to be assembled side by side to provide what is commonly referred to as a gang formation, such gang having a common conduit or passage extending through all the switches to 20 receive the feed wires.

A further object is to provide an electric switch of this general character which shall be particularly simple in construction, inexpensive to manufacture and which shall 25 be efficient in operation.

With these and other objects in view, the invention consists in the various novel features of construction and arrangement or 30 combination, all of which will be fully described hereinafter and pointed out in the appended claims.

In the drawing accompanying and forming a part of this application Fig. 1 is a 35 front elevation illustrating a plurality of switches assembled in gang formation; Fig. 2 is a vertical sectional view through one of the switches, the switch mechanism proper being shown in side elevation; Fig. 3 is an enlarged fragmentary transverse sectional view taken on the line 3—3 of Fig. 1; and Fig. 4 is a fragmentary perspective view of two adjacent boxes.

Describing the various parts by reference 45 characters, 1 denotes generally a switch mechanism having contacts 2 and 3 which are adapted to be interconnected by one or more movable knife blades 4. The particular switch illustrated is of the toggle type 50 and is operated by means of a lever 5 to engage or disengage the knife blades 4 with contacts 2 and 3, thereby to close or open the circuit. In the present instance upward movement of the lever 5 as viewed in Figs. 55 1 and 2 will close the circuit and downward

movement of such lever will open the circuit. The switch shown is of standard type readily obtainable in the market and a detailed description thereof is deemed unnecessary.

The switch 1 is enclosed in a metallic box comprising side walls 7, end walls 8 and 9, and a rear wall 10. The front of the box is normally closed by a cover 11 which is hinged to end wall 9 as indicated at 12, and this cover is provided with a slot 13 through which lever 5 projects. We preferably provide the lever 5 with an upwardly directed portion that is normally adjacent to or in contact with the upper edge of slot 13 when the switch is in closed circuit position. With this arrangement it is thought to be obvious that by opening the cover 11, the lever 5 will be forced downward and thereby open the switch 4 and hence render it 75 impossible for anyone to gain access to the box without first opening the circuit. An outwardly directed lug 15 projects from one edge of slot 13 so that the switch may be sealed in open circuit position by inserting 80 the usual seal through an aperture in the switch lever 5 and an aperture in the lug 15.

The upper end wall 8 is provided with a suitable opening to receive an electric meter denoted generally at 16. Each side wall 7 is 85 provided adjacent its lower end with an opening 17 which merges with the front edge of such wall. The opening in one of these walls is bordered on the outer side thereof with a flange 18 that extends entirely about the peripheral edge thereof while the opening 17 in the opposite wall of the box is devoid of such flange. The purpose of these openings 17 is to provide a substantially continuous conduit through 90 a plurality of boxes when assembled for gang formation. Referring to Figs. 3 and 4, it will be noted that when a number of boxes are to be assembled in gang formation, the flange 18 of one box will interfit with the opening 17 of an adjacent box, thereby 100 permitting the boxes to be assembled in close relationship with the side walls 7 of each box in contact. The boxes are held together by suitable bolts and nuts extending through 105 adjacent side walls, and these screws also serve to electrically bond the boxes together and provide a convenient terminal for a ground connection. The flange 18 interfitting with an adjacent opening 17 provides a 110

continuous metallic conduit between the boxes as clearly shown in Fig. 3, and this conduit is adapted to receive the feed wires denoted generally at 20. If desired each box may 5 also contain a suitable fuse block (not shown) which may be interposed in the usual manner between the feed wires 20 and the switch 1 in each box. When a single switch is installed, the openings 17 in the 10 side walls may each be closed by a suitable plate as indicated in dot-and-dash lines in Fig. 2, such plate being fastened by screws if desired, or this plate may be formed as a knock-out portion in the usual manner.

15 A switch box constructed in accordance with our invention enables the switches to be assembled in gang formation with the side walls of adjacent boxes in contact, and hence such gang formation will occupy a 20 minimum of space. Furthermore no separate interconnecting conduit is required between adjacent boxes in order to provide a continuous conduit for the feed wires and the boxes can be erected in minimum time.

25 The switch handle projecting through the cover provides a convenient operating handle which is readily accessible and with our particular arrangement above described provides a safety feature so that it is impossible 30 to gain access to the box without opening the circuit.

While we have used the terms "upper" and "lower" in the specification and appended 35 claims to denote the upper and lower portions of the switch as viewed in the drawing, it will be understood that such terms are used in their broadest sense and are not

intended to limit the position in which it is necessary to operate the switch.

Having thus described my invention, what 40 I claim is:—

1. A switch box of the character described comprising a substantially rectangular metallic box having side walls each provided with an aperture in transverse alignment, a 45 flange formed on one side wall about the periphery of the aperture therein and adapted to enter a similar aperture in an adjacent box thereby to provide a continuous 50 passage between adjacent boxes when a plurality of such boxes are assembled in gang formation with their side walls abutting, a cover normally closing the front of said box and having a vertically extending elongated opening therein adapted to receive 55 a switch handle therethrough.

2. A plurality of switch boxes of the class described, adapted to be assembled in gang formation with the side walls thereof in contact one with the other, the abutting 60 walls of said boxes each being provided with an aperture in transverse alignment, a flange on one of said side walls adjacent the aperture therein adapted to enter the aperture in the adjacent side wall thereby to provide 65 a continuous passage therebetween, a cover for each of said boxes normally closing the front thereof, each of said covers having an elongated opening therein adapted to receive 70 a switch handle therethrough.

In testimony whereof, we hereunto affix our signatures.

BEN E. SPERO.
LEON SPERO.
